[57] CLAIM

The ornamental design for a vehicle article carrier, as shown.

DESCRIPTION

FIG. 1 is a top plan view of a vehicle article carrier showing my new design;

FIG. 2 is a side elevational view thereof;

FIG. 3 is an end elevational view thereof taken in the direction of the arrow 3—3 in FIG. 2, and

FIG. 4 is an end elevational view thereof opposite to that of FIG. 3.
